UNITED STATES PATENT OFFICE.

ARTHUR E. MEIER, OF CHICAGO, ILLINOIS, ASSIGNOR TO EDWARD J. KOCH & COMPANY, OF CHICAGO, ILLINOIS, A PARTNERSHIP.

DESIGN FOR A CUT-GLASS DISH.

40,671.

Specification for Design.

Patented May 3, 1910.

Application filed March 10, 1910. Serial No. 548,509. Term of patent 7 years.

To all whom it may concern:

Be it known that I, ARTHUR E. MEIER, a citizen of the United States, residing at Chicago, in the county of Cook and State of Illinois, have invented a new, original, and ornamental Design for a Cut-Glass Dish, of which the following is a specification, reference being had to the accompanying drawing, forming part thereof.

The figure is a plan view of a cut-glass dish, showing my new design.

I claim:

The ornamental design for a cut-glass dish, as shown.

ARTHUR E. MEIER.
